UNITED STATES PATENT OFFICE.

LOUIS V. ARONSON, OF NEWARK, NEW JERSEY.

SPARKING RATTLE.

Application filed November 14, 1921. Serial No. 515,084.

To all whom it may concern:

Be it known that I, LOUIS V. ARONSON, a citizen of the United States, residing at Newark, in the county of Essex and State 5 of New Jersey, have invented certain new and useful Improvements in Sparking Rattles, of which the following is a specification.

The invention relates to toys of the watchman's rattle type, and has as an object the 10 provision of such a toy that will produce a shower of sparks while the sound is being produced.

Illustrative embodiments of the invention are shown in the accompanying drawings, 15 in which—

Fig. 1 is a plan view;

Fig. 2 is a side view;

Fig. 3 is a detail section on line 3—3 of Fig. 2 looking in the direction of the arrow; 20 Fig. 4 is a detail section on line 4—4 of Fig. 1;

Figs. 5 and 6 are a plan and a side view respectively of a modification, and

Fig. 7 is a detail bottom plan view of the 25 device shown in Fig. 5, partly broken away.

As shown in Fig. 1, the invention comprises a frame made up of members 10 and 11, joined together by means of a bolt 12 and by each being screwed to a block 13. 30 The block 13 provides weight to cause the device to spin about the handle 14 when whirled in the well known manner common to watchmen's rattles. Rigid with the handle 14 is a rod 15 which is journaled in frame 35 member 11 and an inwardly turned extension 16 of said frame member.

Rigidly secured to the rod 15 is a gear wheel 16 which meshes with a pinion 17, said pinion being rigidly secured to a shaft 18 40 journaled in the frame member 11 and in the frame member 10. Also rigidly secured to the shaft 18 is a disk 19 provided with a roughened surface 20 on one face, which roughened surface may comprise an annular 45 member of emery paper cemented to said disk.

A cross member 21 is mounted upon the frame member 10 either formed integral therewith or secured thereto as shown in the 50 drawing, and sleeves 22 are mounted in the frame member and in the ends of the cross member and project through these parts into the proximity of the face of the disk 20. To produce sparks a small portion of pyro-

phoric metal 23 is placed in each of the 55 sleeves 22 and is spring pressed against the face of the disk.

A convenient means of placing pressure upon the pyrophoric metal is shown in the form of a spring 24 having four arms, one 60 of each of the arms extending into a slot 25 in one of the sleeves 22 and bearing upon the end of the pyrophoric metal. To anchor the spring the central portion thereof is shown as perforated and pressed over the 65 projecting end of the shaft 18, through which end a cotter pin is passed, preferably with a washer between the pin and the spring.

When the handle 14 is grasped and the 70 rattle is whirled friction between the roughened surface 20 and the pyrophoric metal will throw off a shower of sparks, the sparks being provided in the form shown at four different points.

To cause the rattling sound a spring 27 75 is shown secured to a side of the block 13 and pressing against the gear wheel 16.

In the form of the invention shown in Figs. 5, 6 and 7 the frame 28 is formed in 80 one piece bent upon itself at 29 and a handle 30 carries rigid therewith a rod 31 which is journaled in the two ends of the frame 28, being prevented from longitudinal movement by studs 32 and 33.

Rigidly secured to the rod 31 is a gear 85 34 meshing with a pinion 35 upon the shaft of which pinion is mounted a gear 36 meshing with a pinion 37. The shaft 38 carrying pinion 37 projects through the frame 28 and carries rigidly secured thereto an emery wheel 39. If desired the emery wheel may be produced by providing a disk of wood with a facing of emery paper. The shafts of the pinion 35 and gear 36, as well 90 95 as the shaft 38, are journaled in the frame 28 as shown.

A piece of pyrophoric metal 40 may be mounted upon the end of a pin 41, which pin is rigidly secured to the end of a spring 100 42 anchored upon the frame 28. A convenient means of attaching the spring 42 to the frame is that shown, wherein a piece of material 43 is struck upwardly from the middle of the frame and the spring 42 is 105 riveted to said projecting portion.

When the handle 30 is grasped and the frame 28 is whirled thereabout the wheel

39 will be rapidly revolved, causing friction upon the element 40 and therefore producing sparks.

To produce a sound when the toy is operated a toothed wheel 44 may be rigidly secured to the rod 31 and a spring 45 secured to a bar 46 comes into contact with each tooth as the wheel 44 revolves, thereby producing the well known rattling sound. The bar 46 may be formed of such a width as to be rigidly secured to both sides of the frame member 28, and thereby form an effective spacing device for the end of the frame 28 carrying the mechanism.

15 Minor changes may be made in the physical embodiment of the invention without departing from its spirit.

I claim as my invention:

1. A toy comprising, in combination, a 20 watchman's rattle, a disk mounted upon said rattle, means to revolve said disk when said rattle is operated, and means mounted on said rattle and cooperating with said disk to produce sparks when the rattle is operated.

2. A toy comprising, in combination, a watchman's rattle, a disk mounted upon said rattle, means to revolve said disk when the rattle is operated, a roughened surface 30 carried by said disk, a pyrophoric element spring pressed against said surface whereby sparks will be produced when said rattle is operated.

3. A toy comprising, in combination, a 35 weight, frame members having one end of each secured to opposite sides of said weight and having their other ends connected, a

handle carrying a rod journaled in the end of the thus formed frame, a gear wheel mounted to revolve with said rod, a spring 40 pressed against said gear wheel to cause sound when the gear wheel is operated, a shaft journaled in said frame, a pinion carried by said shaft meshing with said gear wheel, a disk rigidly mounted upon said 45 shaft and having a roughened surface, a pyrophoric element spring pressed against said roughened surface to produce sparks when the toy is operated.

4. A toy comprising, in combination, a 50 frame, a disk mounted in said frame having a roughened surface, means to revolve said disk when said toy is operated, a sleeve mounted in said frame adjacent said roughened surface and having a longitudinal slot 55 therein, a pyrophoric element loosely seated in said sleeve, and a spring projecting into said slot pressing said element against said roughened surface.

5. A toy comprising, in combination, a 60 frame, a disk mounted in said frame, means to revolve said disk when said toy is operated, a plurality of sleeves mounted in said frame each sleeve having a longitudinal slot, a pyrophoric element loosely seated in each 65 sleeve, a spring having a plurality of arms, the end of each arm projecting into one of said slots and pressing the pyrophoric element in each sleeve into engagement with said roughened surface, means to hold the 70 center of said spring in fixed relation to said frame.

LOUIS V. ARONSON.
